UNITED STATES PATENT OFFICE.

FRANK STARIN, OF SPRINGFIELD, MASSACHUSETTS.

GRINDING-MACHINE.

1,229,162.

Specification of Letters Patent.

Patented June 5, 1917.

Application filed November 1, 1916. Serial No. 128,852.

To all whom it may concern:

Be it known that I, FRANK STARIN, a subject of the Emperor of Austria, and a resident of Springfield, in the county of Hampden and State of Massachusetts, have invented a new and Improved Grinding-Machine, of which the following is a full, clear, and exact description.

The invention relates to machines for grinding and polishing raw castings of the rings of ball bearings such, for instance, as shown and described in the application for Letters Patent of the United States, No. 72,260 and No. 93,886, filed by me on January 15, 1916, and April 27, 1916, respectively.

The object of the invention is to provide a new and improved grinding machine arranged to simultaneously grind three of the four faces of a ball bearing ring without changing the latter in its holding chuck.

In order to accomplish the desired result, use is made of a revoluble chuck adapted to engage and hold the ring at one side thereof, a plurality of revoluble spindles at angles one to the other and carrying grinders or grinding wheels, and actuating means for bodily moving the said spindles to engage one of the grinding wheels with the outer peripheral face of the ring, to engage another grinding wheel with the inner face of the ring, and to engage a third grinding wheel with the other side of the ring.

A practical embodiment of the invention is represented in the accompanying drawings forming a part of this specification, in which similar characters of reference indicate corresponding parts in all the views.

Figure 1 is a plan view of the grinding machine;

Fig. 2 is a sectional side elevation of the same on the line 2—2 of Fig. 1;

Fig. 3 is a cross section of the same on the line 3—3 of Fig. 5;

Fig. 4 is a similar view of the same on the line 4—4 of Fig. 5;

Fig. 5 is a sectional plan view of the grinding machine on the line 5—5 of Fig. 2;

Fig. 6 is a sectional side elevation of the feed mechanism for the carriage carrying the grinding wheel used for finishing the outer peripheral face of the ball bearing ring, the section being on the line 6—6 of Fig. 1;

Fig. 7 is a perspective view of the fixed

cam for engagement by the cam end of the feed lever of the feed mechanism shown in Fig. 6;

Fig. 8 is a cross section of the feed mechanism for the carriage carrying the grinding wheel used for finishing the outer side of the ball bearing ring, the section being on the line 8—8 of Fig. 1;

Fig. 9 is a side elevation of part of the mechanism for imparting movement to the carriage carrying the peripheral face grinding wheel;

Fig. 10 is a similar view of part of the mechanism for imparting movement to the carriage for the side grinding wheel;

Fig. 11 is a similar view of the mechanism for imparting movement to the carriage for the outer side grinding wheel, part being shown in section;

Figs. 12 and 13 are face views of the coacting disks of the carriage feeding mechanism; and

Fig. 14 is a stud for adjustably connecting the coacting disks with each other.

The raw casting of a ball bearing ring 20 is held at one side in a revoluble chuck 21, and the inner face of the ring 20 including the ball race is ground or finished by a tool, preferably in the form of a revoluble grinding wheel 22 secured on one end of a spindle 23 journaled in a head stock 24 and provided with a pulley 25 connected by a belt and pulley with an overhead countershaft for continually rotating the spindle 23 and its grinding wheel 22. The outer side of the ring 20 is finished by a tool in the form of a grinding wheel 26 attached to a spindle 27 journaled in a head stock 28 and provided with a pulley 29 connected by belt and pulley with an overhead countershaft for continually rotating the spindle 27 and its grinding wheel 26. The peripheral face of the ring 20 is finished by a tool in the form of a grinding wheel 30 secured on a spindle 31 journaled in a head stock 32 and provided with a pulley 33 connected by belt and pulley with an overhead countershaft for continually rotating the spindle 31 and its grinding wheel 30.

The spindles 23 and 31 are normally parallel one to the other and to the axis of the chuck 21 (as shown in Fig. 1), while the spindle 27 is at an angle to the axis of the chuck 21 and to the spindles 23 and 31, and one edge of

the grinding wheel 26 serves to cut the outer side of the ring 20 to finish said outer side.

The chuck 21 is mounted on a spindle 34 journaled in a head stock 35 and provided with a pulley 36 connected by belt and pulley with a countershaft for continually rotating the spindle 34 and the chuck 21 holding the ring 20. The head stock 35 is mounted to slide in a longitudinal direction on a carriage 37 and is adjusted thereon by the use of a manually controlled screw rod 38 screwing in a nut 39 forming part of the head stock 35, as plainly shown in Fig. 2. The carriage 37 is mounted to slide on transverse guideways 40 forming part of the bed plate 41 on which the machine is mounted, and the carriage 37 is transversely adjustable on the guideways 40 by the use of a screw rod 42 screwing in a nut 43 forming part of the carriage 37. The outer end of the screw rod 42 is provided with a worm wheel 44 (see Fig. 3) in mesh with a worm 45 formed or secured on a longitudinally extending shaft 46 journaled in suitable bearings arranged on the bed plate 41. The left-hand end of the shaft 46 is provided with a suitable handle 47 under the control of the operator for turning the shaft 46 with a view to rotate the screw rod 42 and thereby shift the carriage 37 and its head stock 35 in a transverse direction. It is understood that on turning the screw rod 38, the head stock 35 is shifted in a longitudinal direction so as to move the chuck 21 and the ring 20 held thereby in proper position relative to the grinding wheels 22, 26 and 30. The head stock 24 carrying the spindle 23, provided with the binding wheel 22, is mounted to slide transversely on guideways 50 formed on the top of a slide 51 mounted to slide longitudinally in guideways 52 formed on the top of a support 53 secured at its forward end on a vertically disposed pivot 54 journaled in a suitable bearing 55 arranged on a shaft 56 mounted to slide longitudinally in guideways 57 forming part of the body plate 41. The head stock 24 is provided with a nut 60 in which screws a feed screw 61 provided at its forward end with a handle 62 under the control of the operator to permit of shifting the head stock 24 in a transverse direction to correctly set the grinding wheel 22 relative to the inner surface of the ring 20. The slide 51 is provided with a set screw 63 adapted to abut against the right-hand end of the support 53 to limit the movement from the right to the left of the slide 51. The top of the slide 51 is provided with a pin 64 projecting through a slot 65 formed in a transverse lever 66 fulcrumed at its rear end at 67 on the top of the support 53. By the operator manipulating the handle 66 the slide 51 can be lifted from the left to the right or back to the adjusted position, that is, until the set

screw 63 abuts against the right-hand end of the support 53.

By reference to Fig. 2, it will be noticed that the support 53 rests with its left-hand end on the carriage 56 and is thus free to swing in a lateral direction so that the grinding wheel 22 can follow the shape of the ball race on the inner face of the ring 20 to correctly grind the said ball race and using the entire half round peripheral face of the grinding wheel 22, thus insuring uniform abrading of the peripheral face of the grinding wheel 22. On the lower reduced end 68 of the pivot 54 is secured a pinion 70 in mesh with a rack 71 mounted to slide longitudinally in bearings 72 arranged on the frame of the bed plate 41 (see Fig. 5). The rack 71 is pivotally connected by a pitman 73 with a stud 74 having its head slideable in a diametrical groove 75 formed in the under side of a disk 76 (see Fig. 11) secured on the lower end of a shaft 77 journaled in a suitable bearing 78 forming part of the framework of the bed plate 41.

The stud 74 passes centrally through a disk 79 provided with a diametrical tongue 80 slidably engaging the groove 75 in the disk 76. On loosening the stud 74 the disk 76 and with it the stud 74 can be adjusted more or less out of center relative to the center of the disk 76 to increase or decrease the stroke given by the stud 74 and the pitman 73 to the rack 71. On the upper end of the shaft 77 is secured a pinion 81 in mesh with a gear wheel 82 mounted to rotate on a vertical shaft 83 journaled in a suitable bearing of a support 84 forming part of the framework of the machine. On the top of the gear wheel 82 is secured a bevel gear wheel 85 in mesh with a pinion 86 secured on one end of a main driving shaft 87 journaled on the framework and carrying a manually controlled clutch 88 adapted to be engaged with a clutch member 89 arranged on the cone pulley 90 connected by belt with other machinery. When the clutch 88 is in engagement with the clutch member 89 and the cone pulley 90 is rotated then a rotary motion is given to the main driving shaft 87 which by the pinion 86 and the bevel gear wheel 85 rotates the gear wheel 82. The rotary motion of the latter is transmitted by the pinion 81 to the shaft 77 to rotate the disks 76 and 79 with a view to impart a reciprocating motion to the rack 71, as previously mentioned.

The gear wheel 82 is in mesh at its right-hand side with a pinion 91 secured on the upper end of a vertically disposed shaft 92 journaled on the bearing support 84. The lower end of the shaft 92 is provided with a disk 93 having a diametrical groove 94 engaged by a tongue 95 formed on a roller 96 attached eccentrically to the disk 93 by a stud 97 engaging the groove 94. The pe-

- peripheral face of the roller 96 is engaged by the peripheral face of a roller 98 mounted to rotate loosely on the hub 99 of the pinion 70, and this roller 98 is held in engagement 5 with the peripheral face of the roller 96 by a spring 100 attached at one end to the lower end 68 of the pivot 54 and fastened at the other end to the bearing support 84 (see Fig. 2). When the gear wheel 82 is rotated, 10 as previously explained, then a rotary motion is transmitted by the pinion 91 to the shaft 92 whereby the disk 93 is rotated and a rotary motion is given to the roller 96 held eccentrically on the disk 93. This 15 eccentric motion of the roller 96 causes a forward and backward movement of the pivot 54 so that a forward and backward sliding movement is given to the carriage 56 and the support 58, which latter, however, 20 in addition is free to swing by the action of the turning movement given to the pivot 54.
- The head stock 28 is mounted to slide on guideways 110 formed on the top of a slide 111 mounted to slide transversely on a carriage 112 (see Fig. 3) mounted to slide transversely on guideways 113 arranged on the bed plate 41. The under side of the carriage 112 is provided with a stud 114 on which is mounted to turn a roller 116 adjustably fastened to the top extension 117 of the pinion 81 by the use of a stud 118 engaging a diametrical groove 119 formed in the top extension 117 of the pinion 81. The under side of the roller 116 is provided 30 with a dovetail tongue 120 engaging the correspondingly shaped groove 119 so as to permit of adjusting the roller 116 diametrically on the pinion 81, the said roller 116 being eccentrically mounted relative to the 35 pinion 81 by the use of the stud 118. Thus any desired throw can be given to the carriage 112 by changing the position of the stud 118 and that of the roller 116 mounted on the pinion 81. A spring 121 is attached 40 at one end to the bed plate 41 and at its other end to the carriage 112 to hold the roller 115 thereof at all times in contact with the roller 116. It is understood that by the 45 arrangement described the carriage 112 and 50 the parts supported thereon are moved bodily in a transverse direction so that one corner of the grinding wheel 26 is moved across the outer side of the ring 20 to finish the said outer side.
- 55 The slide 111 is adjustably mounted on the carriage 112 and for this purpose use is made of a screw rod 122 mounted to turn on the carriage 112 and screwing in a nut 123 formed on the under side of the slide 111. 60 The rear end of the screw rod 122 is provided with a suitable handle 124 under the control of the operator for turning the screw rod 122 with a view to shift the slide 111 in a transverse direction to correspondingly set 65 the grinding wheel 26 relative to the size of
- the ring 20 under treatment at the time. The head stock 28 is held adjustable on the guideways 110 by the use of a feed screw 125 screwing in a nut 126 formed on the head stock 28 (see Fig. 3) and the said feed screw 125 is journaled in the slide 111 and is provided at its outer end with a handle 127 under the control of the operator for turning the feed screw 125 with a view to move the head stock 28 in the direction of the axis 70 of the spindle 27 to move the cutting edge 75 of the grinding wheel 26 in proper relation to the outer side of the ring 20.
- The head stock 28 is mounted to slide lengthwise on guideways 130 formed on the top of a slide 131 mounted to slide transversely on guideways 132 formed on a carriage 133 mounted to slide longitudinally in guideways 134 formed on the bed plate 41 (see Fig. 3). The under side of the carriage 133 is provided with a stud 135 on which is mounted to rotate a roller 136 in frictional contact with the peripheral face of a roller 137 fastened eccentrically by a stud 138 to the top extension 139 of a pinion 140 mounted to rotate on a vertical shaft 141 journaled on the main frame of the grinding machine. The pinion 140 is in mesh with the gear wheel 82 so that when the machine is running a reciprocating motion is given to the carriage 133 by the action of the eccentric roller 137 on the roller 136. A spring 132 is attached at one end to the bed plate 41 and at the other end to the carriage 133 to hold the roller 136 at all times in contact with the roller 137. The stud 138 is adjustably mounted in a pivotal groove 143 formed in the top of the extension 139 of the pinion 140 and the under side of the roller 137 is provided with a tongue 144 engaging said groove 143. When the machine is running a reciprocating motion is given to the carriage 133 in a lengthwise direction to move the grinding wheel 30 bodily in the same direction with a view to grind the peripheral 90 face of the ring 20.
- In order to adjust the head stock 28 on the guideways 130 of the slide 131 use is made of a screw rod 150 screwing in a nut 151 (see Fig. 3) formed on the under side of the head stock 28. The screw rod 150 is mounted to turn in the slide 131 and is provided at its outer end with a handle 152 under the control of the operator for turning the screw rod 150 with a view to shift the head stock 28 in a longitudinal direction 95 to move the grinding wheel 30 into proper starting position relative to the ring 20. The slide 131 is transversely adjusted on the carriage 133 by the use of a screw rod 160 screwing in a nut 161 formed on the under side of the slide 131. The screw rod 160 is mounted to turn on the carriage 133 and is provided at its other end with a handle 162 under the control of the opera- 100 105 110 115 120 125 130

tor for manually shifting the slide 131 in a transverse direction on the carriage 133 whenever it is desired to do so to properly move the grinding wheel 30 in proper starting position in a transverse direction relative to the ring 20.

- In order to feed the several grinding wheels 22, 26 and 30 for making different cuts on the corresponding faces of the ring 20 until the said faces are ground to the proper size, use is made of automatic feeding devices practically alike in construction so that it suffices to describe but one in detail, it being, however, understood that the feeding devices are mounted on the feed screws 61, 125 and 160, respectively, special reference being had to Figs. 1, 6 and 8. On the corresponding feed screw 61, 125 or 160 is secured a ratchet wheel 170 engaged by a spring-pressed pawl 171 fulcrumed on a lever 172 mounted to swing loosely on the corresponding feed screw 61, 125 or 160. One end of the lever 172 is pressed on by a spring 173 and the other end of the said lever is provided with a cam 174 adapted to engage a cam 175 secured on the top of the bed plate 41. When the corresponding carriage has reached the end of its stroke the cam 174 of the lever 172 clutches the cam 175 whereby a carrying motion is given to the lever 172 to cause the pawl 171 to turn the ratchet wheel 170 so that the corresponding feed screw 61, 125 or 160 is turned to set the grinding wheel for making another cut on the corresponding face of the ring 20. The oscillating movement of the lever 172 is limited by stops 176 and 177 attached to the corresponding carriage of the grinding wheel 22, 26 or 30.
- In order to stop each feed mechanism after the desired number of cuts have been made, use is made of an arm 178 secured on the corresponding feed screw 61, 125 or 160 and adapted to engage a pin 179 on the pawl 171 to throw the latter out of engagement with the ratchet wheel 170 thus stopping further turning of the corresponding feed screw.

The operation is as follows:

- The grinding wheels 22, 26 and 30 are shown at the beginning of the operation and when the machine is running the several carriages 56, 112 and 133 are moved simultaneously, that is, the carriages 56 and 133 are caused to move from the right to the left while the carriage 112 is moved transversely toward the front so that the grinding wheel 22 grinds the inner face of the ring 20, the grinding wheel 30 grinds the peripheral face of the ring 20, and the grinding wheel 26 grinds the outer side of the said ring 20. When the carriage 56 nears the end of its stroke to the left then a swinging motion is given to the support 53 by turning the pivot 54 as previously ex-

plained to cause the grinding wheel 22 to finish the ball race on the inner face of the ring 20. When the carriages 56, 112 and 133 near the end of their return strokes then the levers 172 engage the corresponding cams 175 thus imparting a swinging motion to the levers which by the pawl 171 turn the ratchet wheels 170 thereby turning the several feed screws 61, 125 and 160. The grinding wheels 22, 26 and 30 at their next forward movement take off another chip, and this operation is repeated until the three faces of the ring 20 are properly finished, at which time the arms 178 engage the pins 179 and throw the pawls 171 out of engagement with the ratchet wheels 170 thus stopping further feeding of the feed screws 61, 125 and 160.

It is understood that by the arrangement described the carriages 56, 112 and 133 are moved in one direction during the time the grinding wheels 22, 26 and 30 are abrading by the positive action of the corresponding sets of rollers 98, 96, 115, 116, 136 and 137, and the return movement of the carriages is accomplished by the action of the corresponding springs 100, 121 and 142.

It is also understood that the studs 74 and 97 are set relative to each other so that at the beginning of the movement of the carriage 56 the stud 74 has a slower longitudinal travel than the stud 97 and hence the pivot 54 is not turned, but when the carriage 56 nears the end of its stroke the stud 74 travels faster in a longitudinal direction than the stud 97 and hence the pivot 54 is turned to swing the support 53 sidewise and with it the cutter 22 to hold the latter at all times in radial position in the ball race of the ring 20. In case the ball race of an outer or inner ring only is to be finished either interiorly or exteriorly then the stud 97 is moved into a central position on the disk 93 to stop the reciprocation of the carriage 56 but to allow the support 53 to swing sidewise. The carriage 56 when not actuated is preferably locked in place by inserting a pin in the holes 190 and 191 formed in the bed plate 41 and the carriage 56 respectively (see Fig. 2).

After the ring 20 has been finished on three of its faces as described then the ring is removed from the chuck 21 and its fourth face is finished in a separate machine, and, if desired, it can be finished in this machine by engaging the previously finished side with the chuck 21 and then finishing off the outer side by the use of the grinding wheel 26. During this operation the other grinding wheels 22 and 30 are not used.

Although in the foregoing I have shown and described the grinding machine as used for grinding three faces of a ball bearing ring, it is evident that I do not limit myself to the use of the machine for this pur-

pose only, as other rings, such, for instance, as roller bearing rings, may be finished by this machine in the same manner.

Having thus described my invention, I claim as new and desire to secure by Letters Patent:—

1. In a grinding machine for finishing a bearing ring, a revoluble chuck adapted to engage and hold the ring at one side thereof, a plurality of revoluble spindles at angles one to the other and carrying grinders, and actuating means for bodily and simultaneously moving the said spindles to engage one of the grinders with the outer peripheral face of the ring, to engage another grinder with the inner face of the ring, and to engage a third grinder with the other side of the ring.
2. In a grinding machine for grinding bearing rings, a revoluble holder for holding the ring at one side, a plurality of revoluble spindles carrying grinders, carriages on which the said spindles are mounted, actuating means for simultaneously imparting movement to the said carriages to engage one of the grinders with the outer peripheral face of the ring, to engage another grinder with the inner face of the ring and to engage the third grinder with the other side of the ring, and automatic feeding means for feeding the said carriages step by step for the grinders to make successive cuts on the corresponding faces of the ring.
3. In a grinding machine for grinding bearing rings, a revoluble holder for holding the ring at one side, a plurality of revoluble spindles carrying grinders, carriages on which the said spindles are mounted, actuating means for simultaneously imparting movement to the said carriages to engage one of the grinders with the outer peripheral face of the ring, to engage another grinder with the inner bearing face of the ring and to engage the third grinder with the other side of the ring, automatic feeding means for feeding the said carriages step by step for the grinders to make successive cuts on the corresponding faces of the ring, and stopping means to automatically throw the feed mechanism out of action.
4. In a grinding machine for grinding a bearing ring, a revoluble chuck adapted to hold the ring, a revoluble spindle carrying a grinder adapted to grind the inner face of the ring, a head stock in which the said spindle is journaled, the head stock being mounted to swing on an axis intersecting the axis of the said chuck at a right angle and intersecting the ball race of the bearing ring at the beginning of the curved portion of the ball race, and means for imparting a traveling motion to the said head stock toward and from the said chuck and impart-

ing a lateral swinging motion to the said head stock for the grinder to grind the ball race on the inner face of the ring.

5. In a grinding machine for grinding a bearing ring, a revoluble chuck adapted to hold the ring, a revoluble spindle carrying a grinder adapted to grind the inner face of the ring, a head stock in which the said spindle is journaled, a carriage mounted to travel toward and from the said chuck, a support pivoted on the said carriage and supporting the said head stock, the axis of the pivot of the said support intersecting the axis of the said chuck at a right angle and intersecting the ball race of the bearing ring at the beginning of the curved portion of the ball race, and means for imparting a traveling motion to the said carriage and a swinging motion to the said support.

6. In a grinding machine for grinding a bearing ring, a revoluble chuck adapted to hold the ring, a revoluble spindle carrying a grinder adapted to grind the inner face of the ring, a head stock in which the said spindle is journaled, a carriage mounted to travel toward and from the said chuck, a support pivoted on the said carriage and supporting the said head stock, the pivot of the support being journaled in the carriage and extending beyond the same, the axis of the said pivot intersecting the axis of the said chuck, and means connected with the projecting end of the pivot for moving the latter forward and backward and turning the same.

7. In a grinding machine for grinding a bearing ring, a revoluble chuck adapted to hold the ring, a revoluble spindle carrying a grinder adapted to grind the inner face of the ring, a head stock in which the said spindle is journaled, a carriage mounted to travel toward and from the said chuck, a support pivoted on the said carriage and supporting the said head stock, the pivot of the support being journaled in the carriage and extending beyond the same, a pinion secured on the extended end of the said pivot, a reciprocating rack in mesh with the said pinion, a roller journaled on the hub of the pinion, a rotating eccentric roller in peripheral engagement with the said pinion roller, and a spring for holding the said pinion roller in contact with the eccentric roller.

8. In a grinding machine for grinding a bearing ring, a revoluble chuck adapted to hold the ring, a revoluble spindle carrying a grinder adapted to grind the inner face of the ring, a head stock in which the said spindle is journaled, a carriage mounted to travel toward and from the said chuck, a support pivoted on the said carriage and supporting the said head stock, the pivot of the support being journaled in the carriage and extending beyond the same, a pinion se-

- cured on the extended end of the said pivot, a reciprocating rack in mesh with the said pinion, a roller journaled on the hub of the pinion, a rotating eccentric roller in peripheral engagement with the said pinion roller, a spring for holding the said pinion roller in contact with the eccentric roller, a revolute wheel, means driven from the said revolute wheel for reciprocating the said rack, and means driven from the said revolute wheel for rotating the said eccentric roller.
9. In a grinding machine for finishing a bearing ring, a head stock carrying a spindle provided with a grinding wheel for finishing the inner ball race of the ring, a support for the said head stock, a carriage, a pivot journaled in the carriage and on which the said support is secured, and means connected with the said pivot for moving the latter bodily forward and for imparting a turning motion to the pivot after the pivot has been advanced.
10. In a grinding machine for finishing a bearing ring, a carriage mounted to slide and adapted to carry a grinding tool, a roller journaled on the carriage, an eccentric roller in peripheral engagement with the said carriage roller, a driven gear wheel, a pinion in mesh with the said gear wheel and provided with a diametrical guideway, and a stud adjustably mounted in the said guideway and engaging the said eccentric roller to attach the latter eccentrically to the said pinion.
11. In a grinding machine for finishing a bearing ring, a carriage mounted to slide and adapted to carry a grinding tool, a roller journaled on the carriage, an eccentric roller in peripheral engagement with the said carriage roller, a driven gear wheel, a pinion in mesh with the said gear wheel and provided with a diametrical guideway, a stud adjustably mounted in the said guideway and engaging the said eccentric roller to attach the latter eccentrically to the said pinion, and a spring pressing the said carriage to hold the said carriage roller in contact with the said eccentric roller.
12. In a grinding machine for finishing a bearing ring, a carriage mounted to slide, a support adapted to carry a grinding tool, a pivot journaled in the said carriage and on which the said support is mounted to swing, a pinion secured on the said pivot, a rack in mesh with the said pinion, an eccentric disk, a revolute disk provided with a diametrical slot, and a stud held adjustably in the said guideway and on which the said eccentric disk is mounted, and a pitman connecting the said stud with the said rack.

FRANK STARIN.
